Albert B. Chance

By Williams, Bradbury, McClellan & Shulke

Atty.s.

UNITED STATES PATENT OFFICE

ALBERT B. CHANCE, OF CENTRALIA, MISSOURI

ANCHOR

Application filed April 7, 1928. Serial No. 268,093.

The present invention relates to anchors and is particularly concerned with the provision of anchors for attachment to logs or other members usually termed "dead men."

5 One of the objects of the present invention is the provision of a "dead man" anchor which is quickly attached to logs or other members which may be buried in the earth and which permits the driving of a guy rod 10 attached thereto into the earth when it is later desired to abandon the anchor.

Another object of the invention is the provision of a "dead man" anchor including means for the distribution of the strain over 15 an extended surface of the "dead man" and quick detachable means for connecting a guy rod to said first mentioned means.

Another object of the invention is the provision of a "dead man" anchor comprising a 20 strain distributing plate and a detachable thrust collar which are easily removed and assembled and which permit the attachment of a guy rod to the "dead man" anchor without the necessity of special tools.

25 Another object of the invention is the provision of simple and effective means for securing an ordinary guy rod having an enlarged end which may be pointed or merely upset to a "dead man" through which the guy 30 rod passes.

Other objects and advantages of my invention will appear more fully from the following description and from the accompanying drawings in which similar characters of 35 reference indicate similar parts throughout the several views.

Referring to the single sheet of drawings:

Figure 1 is a view in perspective partially broken away to show the interior structure 40 of a "dead man" employed with my anchoring device;

Figure 2 is a view in perspective of the pressure distributing plate;

45 Figure 3 is a view in perspective of the entire thrust collar; and

Figure 4 is a view in perspective of one section of the thrust collar.

Referring to Figure 1, 10 indicates in its 50 entirety, a log, timber, metal body or other relatively fixed member which is usually

termed a "dead man". The "dead man" is usually buried in the earth and presents a relatively large surface for engaging the earth above it and increasing the holding power of any member which may be secured thereto.

I desire it to be understood, however, that my invention may be used for attaching guy rods to other members besides those buried in the earth, such as trees, poles, and the like, whenever such procedure may be desirable. Consequently, the term "dead man" is employed throughout this specification and in the claims in the generic sense of including any relatively fixed member to which it may be desirable to attach a guy rod.

The "dead man" 10 is attached to the guy rod 11 by means of a securing device indicated in its entirety at 12. The securing device 12 comprises a metal plate 13 of sufficient thickness and area to distribute the strain transmitted to it by the guy rod over a considerable portion of the "dead man" 10.

The plate 13 may be of any shape but is preferably provided with a central aperture 14 of sufficient size to pass the head 15 of the guy rod 11. The aperture 14 is also formed with a pair of grooves 16 adapted to pass lugs 17 carried by a sectional thrust collar which is indicated in its entirety at 18 in Figure 4. 80

The plate 13 is also provided with apertures 19 adapted to receive screws or other fastening means for securing the plate on the "dead man" 10. The sectional thrust collar 18 may consist of a plurality of sections adapted to 85

be assembled together to form a collar embracing the guy rod 11 and filling the aperture 14 of the plate. In the present instance, two semi-cylindrical sections 20 and 20^a are provided, each having an axial groove 21 of sufficient size so that when the two sections are assembled an axial bore 22 is formed which embraces the guy rod 11. The semi-cylindrical sections 20 and 20^a are each provided with a flange 23 extending at substantially right angles and adapted to engage the plate 13 to limit the movement of the thrust collar relative to said plate, and the outer surface of the flange 23 is preferably formed

90 as shown in Figure 3 with a grooved surface 100

24 complementary to the inner edge of the head 15 upon the guy rod 11. For convenience in casting, the grooves 21 in the thrust collar sections 20 and 20^a may be larger than necessary to receive the guy rod 11, but may be provided with bearing portions 25 and 26 at each end of substantially semi-cylindrical form and adapted to fit about the guy rod 11.

Carried by the thrust collar sections 20 and 10 20^a are a pair of lugs 17 having their lower edges 27 sufficiently spaced from the flange 23 to receive the plate 13 between the lugs 17 and the flange 23. The lugs 17 may be of any shape but are conveniently formed like fins 15 of a V-shaped cross section, tapering toward the top of the thrust collar, and the lugs are, of course, adapted to be passed through the grooves 16 in the plate 13. It will thus be observed that the assembled thrust collar may 20 be passed through the bore 14 of the plate 13, when the lugs 17 register with the grooves 16, after which the thrust collar may be rotated relative to said plate, the lugs 17 passing out of registry with the grooves 16 and engaging 25 below the plate 13 to engage the collar therein.

The assembly and operation of my anchoring device with the "dead man" is as follows: The "dead man" is provided with a bore 28, preferably of the same size as the aperture 30 14 in the plate 13. The guy rod 11 may then have its head 15 inserted through the bore 28 and the aperture 14 and the thrust collar 18 may be assembled upon the guy rod between the head 15 and the plate 13, after 35 which the thrust collar may be passed through the apertures 14 and rotated, as previously described, to retain the collar in assembled relation with the plate and "dead man". The assembled structure of the thrust 40 collar and plate may then be forced into the bore 28, the lugs 17 forming grooves in the bore in which they will be received to prevent the thrust collar from rotating. The plate may then be secured to the "dead man" by 45 screws passing through the holes in the plate and the plate should preferably be secured so that the grooves 16 do not register with the lugs 17. The plate being secured against rotation by its screws, and the thrust collar being secured by frictional engagement of its 50 lugs in the bore, these parts will then be held against relative rotation and the thrust collar cannot be detached from the plate without first removing the plate from the "dead man".

55 The foregoing structure is easily manufactured and assembled and the thrust collar 18 provides a means for transmitting the thrust from the head of the guy rod to the plate 13 which distributes the strain over a substantial area of the "dead man".

60 While I have illustrated and described a specific embodiment of my invention, many modifications may be made without departing from the spirit of the invention, and I do not wish to be limited to the precise details of

construction set forth, but desire to avail myself of all changes within the scope of the appended claims.

Having thus described my invention, what I claim is new and desire to secure by Letters 70 Patent of the United States, is:

1. In a "dead man" anchor, the combination of a relatively fixed member having a bore through the same with a strain distributing plate carried at one side of said member and having an aperture aligned with said bore, a guy rod having an enlarged head adapted to pass said bore and aperture, and sectional means adapted to be received by said bore for preventing withdrawal of said 80 head. 75

2. In a "dead man" anchor, the combination of a relatively fixed member having a bore through the same with a strain distributing plate carried at one side of said member and having an aperture aligned with said bore, a guy rod having an enlarged head adapted to pass said bore and aperture, and sectional means adapted to be received by said bore for preventing withdrawal of said 90 head, said latter means comprising a plurality of members for substantially filling said bore about said rod to prevent withdrawal of said head. 95

3. In a "dead man" anchor, the combination of a relatively fixed member with a plate carried thereby, said member and plate having a bore therethrough, a guy rod having an enlarged head adapted to pass said bore, and a thrust collar comprising elements 100 adapted to be passed in said bore about said rod and being outwardly flanged for engagement with said plate to prevent withdrawal of said head. 105

4. In a "dead man" anchor, the combination of a plate having an aperture in the same with a guy rod having a head adapted to pass said aperture, a sectional thrust collar adapted to be assembled about said guy rod and inserted in said aperture, said collar 110 being adapted to prevent passage of said head through said aperture. 115

5. In a "dead man" anchor, the combination of a plate having an aperture in the same with a guy rod having a head adapted 115 to pass said aperture, a sectional thrust collar adapted to be assembled about said guy rod and inserted in said aperture, said collar being adapted to prevent passage of said head through said aperture, and means on said collar for retaining the same in said aperture. 120

6. In an anchoring device, the combination of a flat metal member having an aperture in the same with a guy rod having a head adapted to pass said aperture, a sectional thrust collar adapted to be assembled about said guy rod and inserted in said aperture, said collar having an enlarged head 125 130

for distributing strain from the head of said rod to said flat metal member.

7. In an anchoring device, the combination of a flat metal member having an aperture in the same with a guy rod having a head adapted to pass said aperture, a sectional thrust collar adapted to be assembled about said guy rod and inserted in said aperture, said collar having an enlarged head 10 for distributing strain from the head of said rod to said flat metal member, said collar having a pair of laterally projecting lugs spaced from the head of said collar and said plate having notches to permit the passage of said lugs.

8. In an anchoring device, the combination of a guy rod having an enlarged head with a metal plate having means for its securement to a relatively fixed member and 20 having an aperture adapted to pass said head, a sectional collar comprising a pair of substantially semi-cylindrical members adapted to be received in said aperture and having grooves adapted to receive said rod, 25 said cylindrical members having outwardly projecting flanges adapted to form an annular flange about said rod below said head to engage said plate.

9. In an anchoring device, the combination of a guy rod having an enlarged head with a metal plate having means for its securement to a relatively fixed member and having an aperture adapted to pass said head, a sectional collar comprising a pair 30 of substantially semi-cylindrical members adapted to be received in said aperture and having grooves adapted to receive said rod, said cylindrical members having outwardly projecting flanges adapted to form an annular flange about said rod below said head to engage said plate, said cylindrical members each having an outwardly projecting lug spaced from said flange sufficient to receive said plate between said lug and said 40 flange, and said plate being provided with grooves to permit passage of said lugs.

In witness whereof, I hereunto subscribe my name this 30 day of March, 1928.

ALBERT B. CHANCE.
